[57] CLAIM

The ornamental design for a ventilation conduit for toilets, as shown.

DESCRIPTION

FIG. 1 is a perspective view taken from the top, front and left side of a ventilation conduit for toilets showing my new design;

FIG. 2 is a perspective view taken from the bottom, rear and right side thereof;

FIG. 3 is a top plan view thereof;

FIG. 4 is a front elevational view thereof;

FIG. 5 is a right side elevational view thereof;

FIG. 6 is a bottom plan view thereof;

FIG. 7 is a rear elevational view thereof; and

FIG. 8 is a left side elevational view thereof.
